CLAIM

The ornamental design for a powered air-purifying respirator attachment clip, as shown and described.

DESCRIPTION

FIG. 1 is a top perspective view of a powered air-purifying respirator attachment clip showing our new design;

FIG. 2 is a bottom perspective view thereof at a reduced scale in an alternative configuration;

FIG. 3 is a top plan view thereof;

FIG. 4 is a side elevational view thereof, the other side elevational view being identical thereto;

FIG. 5 is a bottom plan view thereof; and,

FIG. 6 is a front elevational view thereof, the rear elevational view being identical thereto.
